UNITED STATES PATENT OFFICE.

WILLIAM D. ROSENCRANTZ, OF HOHOKUS, NEW JERSEY, ASSIGNOR TO THE DRAPER COMPANY, OF PORTLAND, MAINE.

SPINDLE.

SPECIFICATION forming part of Letters Patent No. 614,896, dated November 29, 1898.

Application filed February 26, 1898. Serial No. 671,813. (No model.)

To all whom it may concern:

Be it known that I, WILLIAM D. ROSENCRANTZ, a citizen of the United States, residing in Hohokus, Bergen county, and State of New Jersey, have invented certain new and useful Improvements in Spindles; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

This invention relates to spindles for spinning silk and other filaments; and its object is to provide such spindles with bearings whereby the friction heretofore encountered in operating the same is greatly reduced, and accordingly the said spindles can be rotated at a higher rate of speed and with greater steadiness.

The invention consists in the improved ball-bearing for the spindle, which furnishes the lateral support for the same, while said spindle is vertically supported by a step-bearing, substantially as will be hereinafter more fully described, and finally embodied in the clauses of the claim.

In the accompanying drawing, which represents a side elevation, partly in section, of my improved spinning-spindle, *a* is the rail, penetrated by the bolster *b*, flexibly or firmly secured to said rail in any desired or well-known manner. In the annular flange *b'* of said bolster is arranged a channel *h'*, connecting the central vertical hole in said bolster with the oil cup or chamber *h*.

The upwardly-extending portion of the bolster *b* is provided with an annular shoulder *b''*, on which rests the ring or collar *e*, revolvably mounted on the bolster and prevented from a vertical movement by the annular shoulder *f''*, formed within the sleeve *f* of the whirl *f'*. Said sleeve *f* is securely mounted on the spindle *d*, the lower tapering portion *d'* of which rests with its extreme end in the step *c*, provided for within the bolster *b*.

It must be remarked that the diameter of the lower portion *d'* of the spindle is smaller

than the internal diameter of the central hole 50 or opening in said bolster.

Within the enlarged hollow portion *f''* of the sleeve-whirl are arranged a series of antifriction-balls *g*, adapted to bear against the annular ring *e*, and which balls are prevented 55 from dropping out of said sleeve-whirl by means of an annular ring *h*, inserted into said enlarged hollow portion *f''* and secured therein in any desired manner.

The sleeve-whirl *f f'* is provided with a 60 flange *f''*, extending into an annular groove *b''*, arranged in the top portion of the flange *b'* of the bolster *b*, and which annular groove *b''* is in communication with the central hole of said bolster by means of a channel *b''*. It 65 must be also remarked that the series of antifriction-balls *g* are arranged directly opposite or on a line with the band pull and that said antifriction-balls furnish the entire lateral support for the spindle, while its vertical support is furnished in the step-bearing, as hereinafter described. With this construction the friction is reduced to a minimum, especially in view of the fact that the antifriction-balls bear against the revolvably-mounted annular ring or collar *e*, which latter during the operation of the spindle rotates at a very slow speed, and accordingly the bearing for the antifriction-balls is being continuously changed. By this arrangement 75 80 the durability of said spindles is greatly increased.

A spindle of the above construction requires very little oiling, as the lubricant which enters (through the channel *h'*) the bolster *b* is 85 carried upward on the tapering spindle by means of centrifugal force and is thrown by the latter against the inner wall of the sleeve-whirl *f* and returns, after lubricating the ball-bearing and the revolvably-mounted ring or 90 collar *e*, through the annular groove *b''* and channel *b''* to the bolster *b*.

Having thus described my invention, what I claim as new, and desire to secure by Letters Patent, is—

1. The combination with the bolster, of a 95 spindle stepped in said bolster, a sleeve-whirl mounted on said spindle, a series of antifric-

tion-balls arranged in said sleeve-whirl, and an annular ring or collar revolvably mounted on the bolster and interposed between the latter and the antifriction-balls, substantially as 5 and for the purposes described.

2. The combination with the bolster, of a spindle stepped in said bolster, a sleeve-whirl mounted on said spindle and provided with an inwardly-extending annular shoulder, a 10 series of antifriction-balls within said sleeve-whirl and bearing on its annular shoulder, a ring removably arranged within said sleeve-whirl for retaining the antifriction-balls, and an annular ring or collar interposed between 15 the antifriction-balls and the bolster and revolvably mounted on the latter, substantially as and for the purposes described.

3. The combination with the bolster, provided on its upper portion with an annular 20 shoulder, an annular ring bearing on said shoulder and removably mounted on the bolster, a spindle stepped in said bolster, a sleeve-whirl mounted on said spindle and provided with an inwardly-extending shoulder, a 25 series of antifriction-balls within said sleeve-whirl and bearing against said shoulder and the annular ring or collar respectively, and an annular ring removably secured within the sleeve-whirl for retaining said antifriction-balls, substantially as and for the purposes 30 described.

4. The combination with the bolster, provided in its annular flange with an annular groove communicating with the central vertical hole in said bolster through a channel, 35 of a spindle stepped in said bolster, a sleeve-whirl mounted on said spindle and extending into the annular groove in the flange of the bolster, and a series of antifriction-balls interposed between said sleeve-whirl and the 40 bolster, substantially as and for the purposes described.

5. The combination with the bolster, provided in its annular flange with an annular groove communicating through a channel 45 with the central vertical hole of the bolster, of a spindle stepped in said bolster, a sleeve-whirl mounted on said spindle and extending into the said annular groove in the flange of the bolster, a series of antifriction-balls arranged within said sleeve-whirl, and an annular ring or collar interposed between the 50 said antifriction-balls and the bolster, and removably mounted on the latter, substantially as and for the purposes described. 55

In testimony that I claim the foregoing I have hereunto set my hand this 17th day of February, 1898.

WILLIAM D. ROSENCRANTZ.
